UNITED STATES PATENT OFFICE.

CHARLES D. WHITE, OF NORWICH, CONNECTICUT.

SPINNING-RING.

1,351,595.

Specification of Letters Patent. Patented Aug. 31, 1920.

Application filed October 21, 1919. Serial No. 332,225.

To all whom it may concern:

Be it known that I, CHARLES D. WHITE, a citizen of the United States of America, residing at Norwich, in the county of New London and State of Connecticut, have invented certain new and useful Improvements in Spinning-Rings, of which the following is a full, clear, and exact description.

This invention relates to spinning rings, and among its objects is the provision of a ring which will produce smoother running of the traveler, will cause less bowing of the yarn, will save space between the centers of spindles, will enable a lighter traveler to be used for a given size of ring than heretofore, and will cause a faster running of the spindle as compared with spinning rings of prior known forms.

With these and other important objects in view, the invention comprises a ring which is arranged at a suitable angle, preferably about 45° to a vertical plane, and a base portion which lies in a horizontal plane. By combining the angularly disposed ring with a horizontal base plate, I have found in practice that a traveler of the standard form may be employed, and that the pull of the yarn upon the traveler and the centrifugal force will cause the traveler at its ends to bear with substantially equal force upon opposite sides of the base plate. This results in equally dividing the frictional engagement between two points, and the resistance to movement of the traveler is not only thereby reduced, as compared with prior rings, but the life of the ring is prolonged, because the wear is not concentrated along a single line.

In addition to the above advantages, I have found that with a ring so constructed a much lighter traveler can be used than where the ring is horizontally disposed or an inclined or vertical base or support is employed. By using a light traveler economies of production, and increased speed of travel, are secured.

In its preferred form, the spinning ring is produced of a single piece of sheet metal, and is suitably shaped by dies with its parts so disposed that it is strong and durable, and at the same time possesses other advantages such as those which are above enumerated.

Referring to the accompanying drawings, Figure 1 is a plan view of a spinning

ring embodying the present invention, showing also part of a ring rail; and

Fig. 2 is a sectional view on the line 2—2, Fig. 1.

Fig. 3 is an enlarged, detail view of the ring rail.

In its preferred form the spinning ring comprises a base portion 2, an inwardly and downwardly inclined flange 4, which is bent and doubled upon itself, to form the upwardly inclined, conical spinning ring proper 6, whose upper free edge projects a substantial distance above the plane of the portions of the blank which are doubled upon themselves, that is, the downwardly extending flange 4 and the adjacent part of the upturned ring 6. The base, herein shown in the form of a plate 2 occupies a horizontal position, being supported upon the ring rail 3 to which it may be secured by any suitable means, as for example, by screws 8, which pass through slots 9. A traveler 10 embraces the upwardly extending free edge 5 of the spinning ring, and is curved inwardly, and downwardly, and then upwardly to embrace the bent over edge 7, the construction of the ring being such that a traveler of the ordinary commercial form may be used. It will be seen that the ring, when thus formed from a single piece of sheet metal, may be very economically produced by the use of suitable dies, and by reason of the fact that the base portion 2 extends horizontally, and is bent downwardly and inwardly, and then upwardly to form the ring, the latter is strengthened and stiffened by the doubled portions of the metal, at 4, 6.

With an inclined track such as presented by this ring, the path of the traveler is always maintained concentric with the ring, as the pull upon the thread and the centrifugal force will cause the traveler to slide along the ring and to bear at its ends with substantially equal force at the points *a*, *b*, on opposite sides of the base.

By reason of the angular disposition of the ring 6, and the horizontal relation of the base plate, the traveler, whose ends bear with comparatively light pressure against opposite sides of the plate, will move with less frictional resistance than in prior constructions, and hence with higher speed. There will also be less wear on the ring than

where the traveler is caused to bear hard against the ring at a single point, and hence the life of the ring will be longer than in constructions where such condition exists.

5. In addition to these advantages, a ring when constructed in the manner above described will produce smoother running of the traveler, will cause less bow in the yarn, save space between the centers of spindles,
- 10 enable a lighter traveler to be used, and cause a faster running of the spindle as compared with spinning rings of prior known forms. Moreover, there will be more space between the traveler and ring surface,
- 15 than where the ring is horizontal, so that the danger of breakage of yarn, if any knot or obstruction passes through the traveler, is reduced.

While I have shown and described a spinning ring made of sheet metal, and in practice I prefer to produce it of this material, it will be obvious that some of the benefits of the invention may be obtained by forming the ring out of plate metal, or from 25 other forms of material.

What I claim is:—

1. A spinning ring having a base lying in a substantially horizontal plane, and a raceway disposed angularly thereto, and 30 flared from its lower edge outwardly toward its upper edge, said edges projecting above and below the plane of the base.

2. A spinning ring formed of a single piece of metal, and comprising a substan-

tially horizontal base, and a raceway inclined relatively to said base and having its upper and lower edges projecting above and below the plane of said base.

3. A spinning ring made of sheet metal, having a horizontally disposed base portion, 40 an inwardly and downwardly disposed flange, and an upwardly and outwardly disposed ring constituting the track or raceway for a traveler.

4. A spinning ring made of a single piece 45 of sheet metal, and having a horizontally disposed base portion, and a ring formed by doubling upon itself the metal which extends inwardly and downwardly from said base portion, the ring proper being disposed 50 at an inclination to the base and having an upwardly and outwardly flared free edge extending above the plane of said base to form a raceway for the traveler.

5. A spinning ring made of a single piece 55 of sheet metal, and comprising a horizontal base portion 2, downwardly and inwardly bent flange 4, upwardly extending ring 6, the parts 4 and 6 being doubled to form two thicknesses of metal, and the part 6 having 60 its end extended above the plane of the base 2 to form a free edge, the raceway lying in a plane which is inclined to the plane of the base.

In testimony whereof I have hereunto set 65 my hand this 21st day of October A. D. 1919.

CHARLES D. WHITE
